J. F. MITCHELL

SHUTTLE WINDER

Filed Sept. 29, 1920

UNITED STATES PATENT OFFICE.

JOHN F. MITCHELL, OF TOPEKA, KANSAS, ASSIGNOR TO MARSHALL FIELD & COMPANY, OF CHICAGO, ILLINOIS, A CORPORATION OF ILLINOIS.

SHUTTLE WINDER.

Application filed September 29, 1920. Serial No. 413,573.

To all whom it may concern:

Be it known that I, JOHN F. MITCHELL, a citizen of the United States, residing at Topeka, in the county of Shawnee and State of 5 Kansas, have invented certain new and useful Improvements in Shuttle Winders, of which the following is a specification.

This invention relates to improvements in shuttles, more particularly tatting shuttles, and to devices for winding thread thereon, and consists of the novel features of construction and combinations of parts hereinafter described and set forth in the appended claims. The present application is 15 a substitute for my prior application Serial No. 151,457, filed Feb. 28, 1917.

The objects and advantages of the invention will appear from the following description taken in connection with the accompanying drawings wherein one form of the invention is illustrated.

In the drawings—

Figure 1 is a side elevation of the winding device showing the shuttle mounted in operative position thereon;

Fig. 2 is a front view of the apparatus;

Fig. 3 is a detail view showing the construction of the outer end of the shuttle carrying shaft;

Fig. 4 is a fragmentary view showing the construction of the shuttle; and

Fig. 5 is a section taken on the line 5—5 of Fig. 4.

Referring more in detail to the drawings, 35 the winding device is shown as comprising a staff or post 10 having a hand grip 10^a at its lower end and being bifurcated at its upper end to provide strips or fingers 10^b, which latter are bent over to form suitable 40 bearings 10^c. Mounted in these bearings and extending transversely of the staff or post 10 is a shaft 11, having a hand crank 11^a on one end thereof. Keyed or otherwise fixed to the shaft 11 intermediate the bearings 10^c is a collar 11^b adapted to engage the bearings 10^c at its opposite ends and to 45 thus prevent longitudinal displacement of said shaft. The shaft 11 at the end thereof opposite the hand crank 11^a is adapted for engagement within a centrally disposed passage provided in the shuttle 12 so that said shuttle may be revolved upon rotation of the 50 shaft.

The shuttle comprises the usual wings or side plates 12^a, these plates being secured together according to the present invention by means of two web like members 12^b placed face to face and secured to the inner faces of the wings 12^a by means of suitable upstanding flanges 12^c. Each web is provided with a transverse groove or depression 12^d which, when the webs are assembled, provide a transverse passage of non-circular design in cross section, this passage opening exteriorly of the shuttle on each side thereof through the apertures 12^e provided in the wings or side plates 12^a. The webs are also provided at opposite ends with small apertures 12^f, through one or the other of which the end of the thread may be inserted and knotted prior to the commencement of the winding operation. The flanges 12^c of the webs may be welded to the wings or side plates of the shuttle or may be secured thereto by means of solder, rivets, or in any other suitable manner.

The end of the shaft 11, which is adapted to receive the shuttle 12, is slightly reduced along diametrically opposite planes, as shown at 11^e, so as to render said shaft of substantially the same design in cross section as that of the transverse passage in the shuttle. As a means for preventing accidental displacement of the shuttle longitudinally of the shaft after the same has been positioned thereon, the engaging end of the shaft is split longitudinally as at 11^d, the spreading tendency of the two prongs thus formed serving to frictionally maintain the shuttle at any desired point on the shaft.

Carried by the staff or post 10 by means of a lateral projection 13^a is a thread guide 13. The projection 13^a is provided with a flanged portion 13^b adapted to receive the portion 10^d of the post 10 and is provided with a screw-threaded stud 13^c which extends through the slot 10^e of the post so that, by means of the nut 13^d on said stud, said thread guide may be adjusted longitudinally of the post and secured in any desired position. From the outer end of the lateral projection 13^a, the thread guide extends rearwardly, thence upwardly and forwardly in a curved direction opposed to the direction of rotation of the shuttle, and terminates in the path traversed by the

shuttle when the latter is revolved and at a point intermediate the wings thereof and in close proximity to the latter. This curved portion of the thread guide lies in the same plane with the shuttle and is provided, near its opposite ends, with grooves 13^e and 13^f which are adapted to receive and guide the thread as the same is drawn from a spool and wound on the shuttle. A finger 13^e 5 is provided near the groove 13^f and serves to maintain the thread in said groove, while the finger 13^f at the other end of the guide serves to maintain the thread within the groove 13^e. The grooves 13^e and 13^f are 10 preferably formed in the guide by pressing, and the hump or projection 13^g, formed near the end of the guide during the operation of pressing the groove 13^e therein, may serve to spread the ends or points of 15 the shuttle wings as the latter approach the thread passing between the grooves 13^e and 13^f, thus permitting the thread to pass between said points without being gripped or otherwise disturbed by contact therewith. 20 25 However, this spreading of the wings is not essential to the operation of the device and in practice it may be found preferable to mount the thread guide slightly higher on the staff or post 10 than shown in the 30 drawings, so that the end of the guide may pass freely between the shuttle wings without effecting any spreading thereof. It may also be found preferable to form the thread guide as an integral part of the staff or 35 post 10.

In operating the device, it is preferred to grip the portion 10^a of the staff or post 10 and to hold the device in substantially vertical position. The thread as it passes to 40 the guide may, if desired, be held between the fingers and thumb of the hand in which the device is held, so that said thread may be wound on the shuttle with the requisite degree of tightness. In cutting away of the 45 shaft 11 along diametrically opposite planes, as above described, shoulders 11^e are formed, these together constituting a stop which determines the operative position of the shuttle with respect to the thread guide. As 50 will be observed, the shuttle receiving end of the shaft 11 is made longer than is really necessary for the supporting of the shuttle in operative relation with respect to the thread guide, this being done in order 55 that, should it be desired to unwind thread from the shuttle for any reason, the same may be moved outwardly adjacent the end of said shaft, as shown in dotted lines in Fig. 2 of the drawings, whereupon the 60 thread may be readily and quickly unwound without interference of the thread guide. The engaging end of the shaft being split, as above described, makes it possible to move the shuttle from one position to the other without danger of its be-

ing accidentally displaced longitudinally of the shaft during a winding or unwinding operation.

The form of the thread guide and its position relative to the shuttle and the direction of rotation of the latter constitute important features of the present invention. As previously pointed out, the guide lies in the plane of the shuttle and projects rearwardly from its point of attachment to the 70 post 10 and thence upwardly and forwardly in a curved path opposed to the direction of rotation of the shuttle. The end of the guide terminates between the shuttle wings and the thread grooves 13^e and 13^f formed in said guide are disposed in alignment 75 and preferably inclined substantially as shown. Thus the thread as it passes from one of said grooves to the other travels at an angle with respect to the perpendicular so that the thread is in effect sliced between the wing tips as the shuttle is rotated. This is an important advantage. The guide is 80 preferably mounted in a vertical plane which contains the points of contact between the wing tips and by pressing the thread receiving grooves in the guide, as previously 85 described, the thread may be disposed in the immediate plane of the latter and not nearer one side of the shuttle than the other. This coupled with the other features of the construction insures an even winding of the 90 thread back and forth on the shuttle and prevents the thread from piling up or accumulating in the center or to one side. 95 100

It will be obvious to those skilled in the art, that the present invention is susceptible of various changes and modifications, and it is not, therefore, desired to limit the same to the particular construction and arrangement of parts, herein illustrated and described, except where limitations appear in the appended claims.

I claim:

1. The combination with a shuttle having a transverse passage therethrough of non-circular design in cross section, of a winding device for said shuttle, a crank shaft rotatably carried thereby, one end of said shaft being designed to fit within said passage, a thread guide, and a stop for positioning said shuttle on said shaft in operative relation to said guide, said shaft being split longitudinally to frictionally maintain said shuttle against displacement. 110 115 120

2. The combination with a shuttle having a transverse passage therethrough of non-circular design in cross section, of a winding device for said shuttle, a crank shaft rotatably carried thereby, one end of said shaft being designed to fit within said passage, a thread guide, a stop for positioning said shuttle on said shaft in operative relation to said guide for winding said shuttle, said shuttle being movable on said 125 130

shaft to a position inoperative with respect to said guide for unwinding said shuttle, and means for maintaining said shuttle in either of said positions against accidental displacement.

3. In a shuttle winding device, a staff, a crank shaft rotatably carried thereby, a shuttle detachably mounted thereon, and a thread guide carried by said staff and disposed in the plane of said shuttle, said guide being curved from its point of attachment rearwardly, then upwardly and forwardly and terminating within the path of said shuttle intermediate the wings thereof and in close proximity to the points of the latter, said guide being formed near its point of attachment and near its outer extremity with thread receiving grooves.

4. In a shuttle winding device, a staff, a shaft carried thereby and adapted to support a shuttle, means to rotate said shaft, and a thread guide carried by said staff and extending on both sides thereof in a plane disposed at substantially right angles to said shaft, said guide projecting in a direction opposed to the direction of rotation of the shuttle and terminating in the path of the latter intermediate the wings thereof.

5. In a shuttle winding device, a staff, a shaft carried thereby and adapted to support a shuttle, means to rotate said shaft, and a thread guide carried by said staff and extending on both sides thereof in a plane disposed at substantially right angles to said shaft, said guide projecting in a direction opposed to the direction of rotation of the shuttle and terminating in the path of the latter intermediate the wings thereof, and said guide being provided with thread receiving grooves one in advance of said staff and the other to the rear thereof.

6. In a shuttle winding device, a support, a shaft carried thereby and being provided with means for rotating the same, a shuttle detachably mounted on said shaft, and a thread guide carried by said support and projecting in a direction opposed to that of the rotation of said shuttle, said guide terminating in the path of said shuttle intermediate the wings thereof and in advance of said support.

7. In a shuttle winder, a shaft, a support

therefor, a shuttle detachably mounted on said shaft, and a thread guide carried by said support and extending on both sides of the latter in a direction opposed to the direction of rotation of said shuttle and terminating in the path of the latter intermediate the wings thereof, said guide being provided with thread receiving grooves one on either side of said support.

8. In a shuttle winder, a support adapted to be held in the hand of the operator and provided with a grip portion at one end, a shaft carried by said support, a shuttle detachably mounted thereon, means to rotate said shaft, and a thread guide associated with said parts and so arranged relative thereto as to cause the thread as it enters said guide to pass in close proximity to said grip portion.

9. In a shuttle winder, a support, a shaft carried thereby, means to rotate said shaft, and a thread guide mounted on said support at substantially right angles to said shaft and extending on both sides of the vertical plane containing the longitudinal axis of said shaft and in a direction opposed to the direction of rotation of the latter.

10. In a shuttle winder, a support, a shaft carried thereby, means to rotate said shaft, and a thread guide mounted on said support at substantially right angles to said shaft and extending on both sides of the vertical plane containing the longitudinal axis of said shaft and in a direction opposed to the direction of rotation of the latter, said guide being provided with thread receiving grooves one in advance of said plane and the other in the rear thereof.

11. In a shuttle winding device, a support, a shaft carried thereby and adapted to receive a shuttle, means to rotate said shaft, and a curved thread guide terminating in the path of said shuttle intermediate the wings thereof and in a direction opposed to the direction of rotation of said shuttle, said guide being provided with thread receiving grooves for guiding the thread between the wing tips of the shuttle at an angle.

In testimony whereof, I have subscribed my name.

JOHN F. MITCHELL.
